UNITED STATES PATENT OFFICE.

ARTURO MUOJO, OF BROOKLYN, NEW YORK.

VENTILATING SAFETY-WINDOW.

1,152,900.

Specification of Letters Patent.

Patented Sept. 7, 1915.

Application filed May 19, 1914. Serial No. 839,588.

To all whom it may concern:

Be it known that I, ARTURO MUOJO, an Italian subject, residing at Brooklyn, in the county of Kings, State of New York, have 5 invented certain new and useful Improvements in Ventilating Safety-Windows; and I do hereby declare the following to be a full, clear, and exact description of the invention, such as will enable others skilled 10 in the art to which it appertains to make and use the same.

This invention relates to new and useful improvements in windows.

An object of the invention resides in the 15 provision of a window wherein the sash may be swung on a vertical pivot so as to be accessible from within a room for cleaning purposes.

A further object of the invention resides 20 in the provision of means for preventing the entrance of water or dust when the sash is in its closed position.

With these and other objects in view such 25 as will appear as my description progresses, my invention resides in the combination and arrangement of parts as set forth in and falling within the scope of the appended claims.

In the drawing: Figure 1 is a fragmental 30 sectional view of a portion of my device; Fig. 2 is a fragmental elevational view with the glass frame swung partially open; Fig. 3 is a fragmental sectional view taken at right angles to Fig. 1; and Fig. 4 is a fragmental sectional view showing the pivot on 35 which the glass frame is mounted.

Referring to the drawing by reference 40 characters wherein like parts are indicated by like characters throughout the several views: In the drawing, I have illustrated a portion of a sash 1. Secured to the inner edges of the top and bottom of this sash are U-shaped members 2 while secured to the inner side edges are flanges 3 which are 45 provided with integral plates 4, the plates 4 being secured to the edges of the sash. The flanges 3 are arranged on opposite sides of the sash and are soldered or otherwise secured to the U-shaped members 2, at 5. 50 A weather strip 6, U-shaped in cross section is slidably mounted on each of the members 2 and is normally pressed away from the member by springs 7 which are clearly disclosed in Figs. 1 and 3 of the drawing. The 55 members 2 and 6 are so arranged that the legs embrace each other in the manner dis-

closed in Fig. 1 of the drawing and so that the members 6 will be guided in their movement. A bearing member 8 is mounted in the top of the sash and a similar member 60 is mounted in the bottom thereof, the latter being designated by the character 9. A conical head 10 is mounted in each of these bearing members and is provided with an outwardly extending pintle 11. Interposed 65 between this head and the adjacent member 2 is a washer 12. These pintles 11 extend through the members 6 and have a frame 13 secured thereto, which frame is composed of angular metal strips as shown in Fig. 1 70 of the drawing. A second and similar frame 14 is secured to the frame 13 by screws 15 and interposed between these frames 13 and 14 is a glass 16. The frames 13 and 14 constitute the frame for carrying the window 75 glass and will be hereinafter designated as the glass frame. The glass frame is so arranged between the members 6 that the latter will bear upon the upper and lower edges of the frame 13 and be held resiliently 80 in contact therewith by the springs 7. Water and dust will therefore be excluded from the room. The flanges 3 are so arranged that they will contact with the side bars of the window glass frame and not only act as 85 stops to properly position the said frame but will also prevent the entrance of water and dust into the room. The recesses in which the bearing members 8 are disposed are covered by suitable plates 17. The glass 90 frame may be locked in its closed position by a bolt 18 which is engageable with a notch 19 in the glass frame.

From the foregoing description it will be seen that I have provided a novel means for 95 preventing the entrance of water or dust into a room when the window is closed. Furthermore, I have provided novel means for mounting the glass frame.

While I have illustrated and described a 100 particular embodiment of my invention, it has merely been for the sake of convenience and I do not wish to be limited to that particular embodiment as it is obvious that numerous changes may be made within the 105 scope of the appended claims.

What I claim is:—

1. In a window, a sash, a glass frame pivoted on the sash, a U-shaped member secured to the inner edges of the upper and lower 110 cross bars of the sash, a similar member slidably mounted on each of the first men-

tioned members and adapted to bear against the upper and lower edges of the glass frame and resilient means for pressing the said last mentioned members into contact with the 5 said frame.

2. In a window, a sash, a bearing member mounted in each of the upper and lower cross bars thereof, a conical head rotatably mounted in each of the bearing members, a 10 pintle extending from each head, a glass frame secured to said pintles and a spring

pressed weather strip mounted between each of the upper and lower edges of the glass frame and the adjacent edge of the sash, the said weather strips being adapted to slide 15 upon the pintles.

In testimony whereof, I affix my signature, in the presence of two witnesses.

ARTURO MUOJO.
